UNITED STATES PATENT OFFICE

EUGENE A. SAVARY, OF PHOENICIA, NEW YORK

DICE AGITATOR

Application filed May 21, 1931. Serial No. 538,916.

This invention relates to a tubular dice agitator and it causes a die or dice used in playing games for amusement to be thoroughly shaken or agitated by gravitation.

5 It is intended to prevent unfair manipulation of a die or dice. After the dice have been dropped into the top opening of a tube the shaking they receive is entirely automatic and the result is beyond the control of any 10 human agency.

The novel combinations of the invention are more fully described in the following specification and claims and illustrated in the accompanying drawing in which:

15 Fig. 1 represents a vertical section of a device embodying this invention.

Fig. 2 is a plan or top view of the same.

In the drawing is shown a cylindrical tube 5 open at both ends and preferably made of 20 stiff cardboard, but could be made of leather, metal, or of a composition, such as rubber or bakelite, and provided with a fixed sleeve 6 encircling the bottom and top of the tube. In the upper part of the tube is situated a 25 bar 7 having ends 8 looped over the top and hooked into the side of the wall. The lower sleeve in conjunction with the end of the tube serves to support the device in an upright position on a table or other object. The bar is 30 equipped with an eye 9 made by looping said bar centrally.

A movable stem 10 has a similar loop to engage the eye of the bar. The stem has a series of integral branches or projecting prongs 12 35 extending radially from the stem at different levels, formed by doubling the wire back and forth. The tips of the branches are curved so that when they impinge on the interior of the tube they will not injure it. The base of 40 the stem is substantially + shape so that the dice will strike the lower prongs.

The device when used is held in one hand or placed on a table. The die or dice are dropped into the tube at the top opening. 45 They naturally fall downward and in their descent strike the projecting branches which causes the dice to tumble about striking all parts of central stem member which is suspended and is free to move about back and forth and partly around as the dice fall 50

through a passage which momentarily retards or prevents the dice from passing through the tube without striking these projecting branches. Finally the dice come to rest on the table in front of the player. 55

What I claim is:

1. A dice agitator comprising a tubular member, a stationary bar fixed in the tube near the top, a movable stem suspended from the bar, and a series of branched members 60 projecting from the stem.

2. A dice agitator comprising a tubular member, a stationary bar fixed in the tube near the top, a movable stem suspended from the bar, and a series of branched members 65 projecting radially from the stem.

3. A dice agitator comprising a tubular member, a stationary bar fixed in the tube near the top, a movable stem suspended from the bar, and a series of branched members 70 projecting radially from the stem at different levels.

4. A dice agitator comprising a tubular member, a stationary bar secured in the wall 75 of the tube near the top, a wire member hingedly suspended from the bar extending to near the bottom of the tube, and a series of branched integral members projecting radially from the stem at different levels.

5. A dice agitator comprising a cylindrical tubular member open at the top and bottom, a stationary bar secured in the wall of the tube near the top, a wire stem member hingedly suspended from the bar extending to near the bottom of the tube, and a series of branched integral members projecting radially from the stem at different levels the lower branch being substantially + shaped. 85

In testimony whereof I have hereunto set 90 my hand.

EUGENE A. SAVARY.
